UNITED STATES PATENT OFFICE.

EDWARD G. BRINKMAN, OF DECATUR, ILLINOIS.

ROTATABLLE CURLING-IRON HANDLE.

Application filed July 14, 1923. Serial No. 651,470.

To all whom it may concern:

Be it known that I, EDWARD G. BRINKMAN, a citizen of the United States, and a resident of the city of Decatur, in the county 5 of Macon and State of Illinois, have invented certain new and useful Improvements in Rotatable Curling-Iron Handles; and I do hereby declare that the following is a full, clear, and exact description of the same, 10 reference being had to the accompanying drawings, and to the numerals of reference marked thereon, which form a part of this specification.

In beauty parlor and hair dressing establishments a particular type of an all metal imported marcelling or curling iron is used. The curling iron is made of a particular kind of metal preferred by the attendants or operators, since it gives better 20 results than domestic irons. The imported all-metal irons are only provided with metal handles which are integral extensions of the crimping members. In using an all-metal curling iron of the type described the hand 25 of an attendant using the curling iron very often becomes blistered or calloused due to the heat from the handles and also to the constant regripping of the handles during a hair marcelling operation.

This invention relates more particularly to improved rotatable handles of non-conducting material adapted to be removably mounted on the metal handle bars of an all-metal imported curling iron now extensively 30 used in beauty parlors and the like, said rotatable handles serving as a protection for the hand of an operator and also greatly facilitating the handling of the curling iron when a head of hair is to be curled or mar- 35 celled.

It is an object of this invention to provide an all-metal curling iron with rotatable handles.

It is an important object of this invention 45 to equip the integral handle bars of a marcelling iron with stop shoulders between which rotatable handle sleeves are mounted to facilitate the handling of the marcelling iron and also affording a means for protecting the hands of beauty parlor attendants who continuously use the same.

Other and further important objects of this invention will be apparent from the

disclosures in the specification and the accompanying drawings. 55

The invention (in a preferred form) is illustrated in the drawings and hereinafter more fully described.

On the drawings:

Figure 1 is a longitudinal view of a curling iron embodying the principles of this invention. 60

Figure 2 is an enlarged detail sectional view taken on line 2—2 of Figure 1.

Figure 3 is a fragmentary detail section 65 taken on line 3—3 of Figure 2 showing parts in elevation.

As shown on the drawings:

The reference numeral 1 indicates a round solid metal crimping tong or rod with which 70 a semi-cylindrical crimping member 2 contacts. The crimping members 1 and 2 are pivotally connected one to the other by a pivot stud or pin 3 in the usual manner. Integrally formed on the pivoted ends of 75 the crimping members are the bowed or curved ends of round metal handle bars 4. The ends of the handle bars 4 are threaded as at 5.

Braised or otherwise rigidly secured on 80 each handle bar 4 near the curved portion thereof is a stop shoulder, collar or flange 5. A rotatable handle or sleeve 6 made of wood, fiber or any other desired material is engaged on each handle bar 4 and is retained 85 in position by means of an internally threaded retaining ring or nut 7 which is threaded onto the threaded end 5 of the handle bar. The handles 6 are thus rotatable on the handle bars and may be conveniently 90 gripped by the hand of an operator so that the crimping members 1 and 2 may be very readily turned during a marcelling or crimping operation without requiring a constant change of the grip of an operator. 95 The hand of an operator using the improved curling iron is thus protected from the heat conducted to the handle bars 4 from the heated crimping members 1 and 2. The rotating feature of the handles 6 makes the 100 use of the curling iron materially easier and thereby permits the operator to efficiently marcel or crimp a head of hair without subjecting the hand of the operator to burns, 105 blisters or callouses.

I am aware that numerous details of con-

struction may be varied through a wide range without departing from the principles of this invention, and I therefore do not purpose limiting the patent granted otherwise than necessitated by the prior art.

I claim as my invention:

1. A curling or marcelling iron comprising a pair of pivotally connected crimping members, handle bars integral therewith, stop collars rigidly secured on said handle bars near the inner ends thereof, sleeve handles rotatably engaged on said handle bars to the outside of said stop collars, and retaining members engaged on the outer ends of said handle bars to hold the sleeve handles in position.
2. A curling or marcelling iron, comprising a pair of pivotally connected crimping

members having handle bars integrally formed thereon, said handle bars having their outer ends reduced and threaded, stop collars rigidly secured on said handle bars, handles rotatably engaged on said handle bars to the outside of said stop collars, and retaining members engaged in the threaded ends of said handle bars for holding the handles in position, said stop collars, handles and retaining members being of the same diameter.

In testimony whereof I have hereunto subscribed my name in the presence of two subscribing witnesses.

EDWARD G. BRINKMAN.
